GRINDER

Henry John Mankoff, Wichita, Kans.

Application January 21, 1937, Serial No. 121,700

1 Claim. (Cl. 83—11)

This invention relates to grinding machines, and more particularly to grinding machines embodying rotary hammer blades, such as shown and described in my pending application filed September 20, 1936, Serial No. 103,032, now Patent No. 2,158,240, primarily designed for grinding compost, feed or like material.

An important object of the invention is to provide a machine of this character so constructed that extremely wet compost material may be efficiently ground by the machine, without danger of the machine clogging.

A further object of the invention is to provide a plurality of spaced rollers forming the bottom of the rotary hammer chamber, the rollers being constructed in such a way that the rotary hammer blades will operate in close relation with respect to the rollers, at the point where the material enters the hammer blade chamber, thereby insuring the cutting and grinding of the material where the material is heaviest.

A still further object of the invention is to provide a machine of this character having a screening member in the form of rollers, which act to move under the action of the rotary blades, freeing the material and directing the material downwardly between the roller.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a front elevational view of a grinding machine constructed in accordance with the invention.

Figure 2 is a sectional view taken on line 2—2 of Figure 1.

Figure 3 is a fragmental detail view illustrating the means for supporting the rollers.

Referring to the drawings in detail, the grinding machine comprises a body portion indicated generally by the reference character 5, the body portion comprising end plates 6 which are held in spaced relation with each other by means of the plate 7 secured to the rear edges of the plates 6, and the plate 8 secured to the forward edges of the end plates 6.

The lower edges of the end plates 6 are cut away providing legs 9, which hold the body portion in spaced relation with the surface on which

the body portion stands. As clearly shown by the drawings, the plate 7 extends upwardly where it connects with the bottom of the inclined trough 10, which trough has its front end open to provide a clearance for the adjustable apron 11, and at the same time providing a passageway for material entering the body portion of the machine.

The adjustable apron 11 is formed with a substantially wide upper section and a curved lower section 11'. An opening is formed along the lower edge of the curved section 11' and is adapted to receive the rod 20, when the apron is in the position as indicated in full lines in Figure 2. Straps 21 are secured to the apron 11 and under which the rod 22 extends, securing the apron to the rod. When the apron is moved to the position shown by dotted lines in Figure 2 of the drawings, the opening along the lower edge of the curved section 11' accommodates the upper rod 12, while the rod 20 is extended under the straps 21, thus closing the body portion through the hopper.

Mounted within the body portion 5 and disposed between the end plates 6, are rods 12 on which hollow rollers 13 are mounted, the rollers being arranged in a curved line, and spaced apart so that material may pass therebetween. As clearly shown by Figure 2 of the drawings, the rods 12 at one end of the line of rollers, are substantially large and support substantially large rollers 13. Due to this construction, it will be seen that the rollers 13 at the feed end of the body portion, will be disposed near the cutting blades of the hammers, insuring the cutting of the material at this point, to prevent the material from clogging.

It might be further stated that the end plates 6 have curved portions that carry out the general contour of the curved lines of the rollers 13, providing a substantially circular housing in which the blades 14 operate. These blades are mounted on the shaft 15, which extends through the body portion, and is provided with a pulley 16 over which a power belt, not shown, operates to transmit rotary movement to the shaft and blades. Mounted between the end plates 6, is a pivoted plate 17 which acts as a guard to control the material which is fed into the machine, and prevents the material from piling to clog the machine. Hopper 18 is provided at the forward portion of the body portion 5, and is so arranged that material fed into the machine through this hopper, will be directed to the blades 14. This hopper 18 is used for feeding material to the machine, when the material is exceptionally wet.

It might be further stated that the shafts or rods 12 on which the rollers 13 are mounted, have their ends extended through openings in the end plates 6 of the body portion, eliminating the usual supporting plates employed in supporting rods of this type, and on which the material usually collects to clog the machine.

Due to the construction of the rollers, the rollers will retard the material at a point until 10 the material is thoroughly pulverized. When the material has been thoroughly pulverized, the material drops through the spaces between the rollers, and since these rollers are constantly rotating, the material will be carried through 15 the spaces, preventing clogging of the material.

What is claimed is:

A grinding machine comprising a body portion including a beater casing, a rotary grinding member mounted within the body portion, a

trough and hopper communicating with the body portion at opposite sides of a vertical line drawn through the axis of the rotary grinding member, a screening member comprising spaced rollers mounted within the body portion and arranged in the arc of a circle, said grinding member cooperating with the rollers in grinding material fed into the body portion through the trough and hopper, an adjustable deflector member including a curved lower portion, adjustably mounted within the body portion between the trough and hopper, said lower curved portion of the deflecting member being coextensive with the screening member in one of its positions of adjustment, and said deflector being normally arranged in spaced cooperative feeding relation with the trough and adapted to open and close the hopper discharge to the beater casing.

HENRY JOHN MANKOFF.
